CLAIM

The ornamental design for a hair clip, as shown and described.

DESCRIPTION

FIG. 1 is a perspective view showing the left side and top of the hair clip which forms my new design;

FIG. 2 is a top plan view thereof, the bottom view being a mirror image of the top;

FIG. 3 is a rear elevational view thereof;

FIG. 4 is a left side elevational view thereof;

FIG. 5 is a front elevational view thereof; and,

FIG. 6 is a right side elevational view thereof.
